(57) **CLAIM**

We claim the ornamental design for a case for a handheld computer system, as shown and described.

DESCRIPTION

FIG. 1 is an upper right front perspective view in the closed position of a case for a handheld computer system;

FIG. 2 is a lower left rear perspective view in the closed position thereof;

FIG. 3 is a front elevational view in the closed position thereof;

FIG. 4 is a right side elevational view in the closed position thereof;

FIG. 5 is a rear elevational view in the closed position thereof;

FIG. 6 is a left side elevational view in the closed position thereof;

FIG. 7 is a top plan view in the closed position thereof;

FIG. 8 is a bottom plan view in the closed position thereof;

FIG. 9 is an upper right front perspective view in the open position, with a handheld computer system installed and shown in dashed lines as it is not a part of the claimed design;

FIG. 10 is an upper right front perspective view in the open position thereof;

FIG. 11 is a front elevational view in the open position thereof;

FIG. 12 is a right side elevational view in the open position thereof;

FIG. 13 is a rear elevational view in the open position thereof;

FIG. 14 is a left side elevational view in the open position thereof;

FIG. 15 is a top plan view in the open position thereof; and,

FIG. 16 is a bottom plan view in the open position thereof.
